UNITED STATES PATENT OFFICE

171,870

WALL SHELF OR SIMILAR ARTICLE

Howard L. Stert, Burbank, Calif.

Application April 24, 1953, Serial No. 24,654

Term of patent 7 years

(Cl. D33—3)

To all whom it may concern:

Be it known that I, Howard L. Stert, a citizen of the United States, residing at Burbank, State of California, have invented a new, original, and ornamental Design for a Wall Shelf or Similar Article, of which the following is a specification, reference being had to the accompanying drawing, forming a part hereof.

Fig. 1 is a plan view of a wall shelf or similar article showing my new design;

Fig. 2 is a cross-sectional view taken on line 2—2 of Fig. 1; and

Fig. 3 is a vertical cross-section taken on line 3—3 of Fig. 1.

I claim:

The ornamental design for a wall shelf or similar article, as shown.

HOWARD L. STERT.
